FOOD CUTTER

Hazel B. Towler, El Segundo, Calif.

Application January 18, 1949, Serial No. 284

Term of patent 14 years

(Cl. D44—29)

To all whom it may concern:

Be it known that I, Hazel B. Towler, a citizen of the United States and a resident of El Segundo, in the county of Los Angeles and State of California, have invented a new, original, and ornamental Design for a Food Cutter, of which the following is a specification, reference being had to the accompanying drawing, forming a part thereof.

I claim:

The ornamental design for a food cutter, substantially as shown.

HAZEL B. TOWLER.
